(57) **CLAIM**

I claim the ornamental design for a tablet computer with integrated game controller and IR blaster, as shown and described.

DESCRIPTION

FIG. 1 is a front elevational view of a tablet computer with integrated game controller and IR blaster showing my new design;

FIG. 2 is a rear elevational view thereof;

FIG. 3 is a top plan view thereof;

FIG. 4 is a bottom plan view thereof;

FIG. 5 is a right side elevational view thereof; and,

FIG. 6 is a left side elevational view thereof.

1 Claim, 4 Drawing Sheets---
